UNITED STATES PATENT OFFICE.

HAROLD LANGLEY BLOOD, OF OAK PARK, ILLINOIS, ASSIGNOR TO WESTERN ELECTRIC COMPANY, INCORPORATED, OF NEW YORK, N. Y., A CORPORATION OF NEW YORK.

THREAD-FORMING MECHANISM.

Application filed May 8, 1925. Serial No. 28,865.

This invention relates to thread forming mechanisms, and has for its primary object the provision of an improved mechanism for rapidly and economically forming threads upon blanks. 5

In order to attain this object there is provided in accordance with the general features of this invention in a machine for forming threads upon screw blanks, means for 10 successively feeding blanks in a predetermined spaced relationship so that threads are formed on a plurality of blanks during each working stroke of a reciprocating die co-operating with a fixed die.

15 Other objects and advantages of the invention will more fully appear from the following detailed description taken in connection with the accompanying drawings which illustrate one embodiment thereof, and in 20 which

Fig. 1 is a fragmentary plan view of a thread rolling machine embodying the features of the invention with the operating parts shown in position with two blanks between the threading dies and at the beginning of the threading operation upon the second blank;

Fig. 2 is a vertical sectional view taken upon the line 2—2 thereof, and

30 Fig. 3 is a fragmentary plan view of Fig. 1 showing the relative positions of the blank feeding fingers during the positioning of a blank between the threading dies.

Referring to the drawings wherein like reference numerals designate like parts throughout the several views, 10 indicates the frame or bed of a thread rolling machine which may be of any well-known type, all parts not necessary to a complete understanding of the invention having been omitted. A stationary die 11 is suitably mounted in the frame 10 and a movable die 12 carried on a slide member 13 is arranged to be reciprocated upon a suitable guideway (not shown) provided in the frame. A longitudinal reciprocating movement is imparted to the slide 13 through a connecting rod 16 pivotally connected at one end to the slide as indicated at 17, the opposite end of the rod 16 being operatively connected to a crank disk 18 fixed for rotation upon a driving shaft 19 in turn rotated by suitable driving means (not shown) in the direction indicated by the arrow (Fig. 2). Screw blanks 20 are fed from any suitable

hopper mechanism (not shown) down a chute 21, from which they are delivered one at a time to a position between the stationary and movable dies 11 and 12, respectively, by a feeding mechanism to be hereinafter described.

Heretofore, in some machines for rolling threads upon screw blanks a single blank has been fed to a point between the dies at intervals corresponding to each working stroke of the movable die, thereby rolling a thread upon one screw blank for each working stroke of the movable die. In the blank feeding mechanism to be presently described in detail two blanks are fed in succession and properly spaced from each other between the threading dies during the time the moving die has advanced a short distance, so that threads are rolled upon two blanks during each working stroke of the movable die.

The blank feeding mechanism shown in the drawings will now be described. Associated with the lower end or outlet point of the chute 21 (Fig. 2) is a mechanically actuated finger 22 which retains the descending column of screw blanks 20 in the chute and at the proper instant separates the lowermost blank from those behind it and forces the separated blanks outwardly and in front of a pusher finger 23 as shown in Fig. 3, the front end of which is of slightly less width than the space between the faces of the two opposed dies.

In Fig. 1 the finger 23 has just completed pushing a second blank 20 into position between the dies, during which movement it also functions to retain the column of blanks in the chute, the finger 22 at this time being retracted and ready to begin separating a blank from the column and moving it into position at the beginning of the next stroke of the die 12. The actuating means for the fingers 22 and 23 comprises the following: Secured to the shaft 19 for rotation therewith, are cam disks 25 and 26 provided with cam faces 27 and 28, respectively. The cam faces 27 and 28 are adapted to be angularly adjusted relative to each other, the disk 26 being provided with a slot 29 of suitable length through which a screw 30 is inserted and threaded into the disk 25. The head of the screw when clamped against the outer disk 26 retains the disks and thereby the cam faces 27 and 28 in a set angular relation to each other. The purpose of this adjustment

of the cam faces 27 and 28 will be made apparent hereinafter.

- In engagement with the cam faces 27 and 28 is a cam roller 33 rotatably mounted upon 5 a lever 34 fulcrumed at its lower end upon the frame 10 as indicated at 35, the upper end thereof being adjustably secured to a rod 36. One end of the rod 36 is threaded and projects through an opening formed in an offset 10 set portion 37 of the lever 34 and at either side thereof, upon the threaded portion of the rod, is threaded a retaining nut 39. A tension spring 40 suitably connected at opposite ends to the lever 34 and the frame 10 15 acts to cause the roller 33 at all times to follow the cam faces 27 and 28. The purpose of providing for the adjustment of the rod 36 upon the lever 34 will be made apparent hereinafter. The right hand end of the rod 36 is 20 pivotally connected as indicated at 41 to a lever 42 fulcrumed intermediate its ends as indicated at 43 upon the frame 10. To the upper end of the lever 42 is pivotally secured one end of a link 44, the opposite end of the 25 link being provided with an elongated slot 45 within which is adapted to slide a pin 48 fixed in the upper end of a lever 49, the lower end of which lever is fulcrumed as indicated at 50 upon the frame 10. A tension spring 30 51 suitably connected at opposite ends to the lever 49 and the frame 10 normally retains the pin 48 at the right hand end of the slot 45, the purpose of which will be made apparent hereinafter. Pivotally connected to the 35 lever 42 in axial alignment with the pivotal point of the rod 36 therewith, is a slide 52 upon the opposite end of which is formed the pushing finger 23. Adjacent the slide 52 is another slide 53 which is pivotally connected 40 to the lever 49, as indicated at 54, intermediate the ends thereof. The opposite end of the slide 53 carries the finger 22 which is secured thereto by screws 55. The slides 52 and 53 are mounted upon suitable guideways (not 45 shown) provided in the frame 10.

The operation of this mechanism is as follows:

- The shaft 19 revolving in a clockwise direction causes the cam faces 27 and 28 of the 50 disks 25 and 26 to engage the cam roller 33 in succession. The relative angular relation of the cam faces 27 and 28 which determines the interval of time between the engagement of the cam faces with the cam roller is first 55 adjusted by loosening the screw 30 and turning the disk 26 upon the disk 27 to the desired position and thereafter tightening the screw. This adjustment causes the second blank to be introduced between the dies at the proper instant or when the threads of the dies are 60 properly positioned so that a correct thread will be formed upon the blank, while for the first blank the nuts 39 are adjusted upon the rod 36 to cause the blank to be inserted between the dies when the threads of the

dies are properly aligned and at substantially the instant the movable die 12 starts upon its working stroke.

In Fig. 1 the parts are shown in their relative positions at the completion of the feeding movement with two blanks positioned between the threading dies, the moving die having advanced only a short distance. As the disk 18 continues to rotate in a clockwise direction the connecting rod 16 will move 70 the movable die 12 to a point shown in dotted outline in Fig. 1 whereupon the threaded blanks 20, also indicated in dotted outline, will drop free of the dies and into a suitable hopper (not shown). The die 12 thereafter is returned to the position shown in Fig. 3 and thereupon the cam face 27 engages the cam roller 33 and rocks the lever 34 counter-clockwise, causing the rod 36 and attached finger 23 to move toward the left, 75 thereby turning the lever 42 clockwise and moving the link 44 to the right. As the link 44 moves the spring 51 is allowed to turn the lever 49 clockwise about its pivot, thereby causing the finger 22 to move toward the position shown in Fig. 3 to separate a screw blank 20 from the column of blanks in the chute 21 and move it in front of the finger 23 as shown in Fig. 3. The movement of the fingers 22 and 23 in opposite directions as just described takes place substantially at the same time and in timed relation with the movement of the movable die 12. Immediately upon the finger 23 feeding a blank in front of the finger 22 and between the dies, the movable 80 die 12 starts to move toward the right upon its working stroke and the roller 33 rides down the cam face 27 whereupon the spring 40 is permitted to move the rod 36 and attached finger 23 toward the right to insert 85 the first blank 20 between the cooperating dies, the finger 22 being moved toward the left, thereby permitting the lowermost blank in the chute 21 to rest upon the finger 23. The instant the first blank is in position the 90 cam face 28 engages the roller 33 and causes the lever 34 to be rocked counter-clockwise to move the fingers 23 and 22 toward the left and right, respectively, and positioning another blank in front of the finger 23. In the 95 continued rotation of the cam disks the roller 33 rides down the cam face 28, thereby moving the finger 23 toward the right and inserting the second blank 20 between the cooperating dies as shown in Fig. 1 ready for the 100 completion of the working stroke of the die 12. In case a blank 20 becomes lodged in front of the finger 22 for some reason the slot 45 permits the various parts to operate but the finger 22 is not forced toward the right 105 against the lodged blank.

From the foregoing description it will be seen that a mechanism is provided which is of comparatively simple formation in its construction and the arrangement of its parts 110

and one by which the output of a thread rolling machine of the type described may be materially and economically increased.

What is claimed is:

5. 1. In a thread rolling mechanism, a pair of die members having cooperating die faces, means for causing an intermittent relative motion therebetween to form a screw thread on a blank interposed between said faces, and 55
10 means for successively feeding a plurality of blanks from a common point to and between said members at predetermined intervals to effect a predetermined spaced relationship of the blanks between the members during 60
15 each thread forming relative movement of the die members.
  2. In a thread rolling mechanism, a pair of members having cooperating die faces, means for causing a relative reciprocatory motion therebetween for forming a screw 65
20 thread upon a blank interposed between said faces, means for feeding a plurality of blanks between said faces for each thread forming relative movement of the members, and
25 means for varying the spaced relation between the blanks fed between the die members.
  3. In a thread rolling mechanism, a reciprocating slide, a member carried thereby and having a die face, a fixed member having a die face cooperating with the first mentioned 70
30 die face for forming threads on a blank interposed therebetween, means cooperating in timed relation with said slide for feeding a plurality of blanks between said dies for each 75
35 working stroke of the reciprocating slide and means for controlling the timed relation of the feeding means and the reciprocating slide.
  4. In a thread rolling mechanism, a pair of members having cooperating die faces, means holding a supply of blanks, a plurality of oppositely movable reciprocable fingers for feeding blanks from said supply to 80
40 said dies at predetermined intervals, and means for causing a relative reciprocatory motion between the members to form a thread on a blank interposed between said 85
45 faces and for causing said fingers to feed a plurality of blanks between said faces during
50
- said thread forming relative movement of the dies.
5. In a thread rolling mechanism, a pair of members having cooperating die faces, means for causing a relative reciprocatory motion therebetween to form a thread on a blank interposed between said faces, means cooperating in timed relation with said slide for feeding a plurality of blanks between said faces for said thread forming relative movement of the dies, and means for varying the cooperating timed relation between the first and second mentioned means. 55
6. In a thread rolling mechanism, a pair of dies, means for causing a relative reciprocatory motion therebetween to form a thread on a blank, means cooperating in timed relation with said means for successively feeding a plurality of blanks between said dies for said thread forming relative movement 60
70 of the dies, and means for adjusting said last mentioned means to vary the time interval between successive feeding movements thereof.
7. In a thread rolling mechanism, a pair of dies, means for causing a relative motion therebetween to form a thread on a blank, means for feeding blanks between the dies and a cam member actuated by the first mentioned means for causing the last mentioned 75
80 means to successively feed a plurality of blanks during said thread forming relative movement of the dies.
8. In a thread rolling mechanism, a pair of dies, means for causing a relative motion therebetween to form a thread on a blank, means for feeding blanks between the dies, a composite cam member comprising a plurality of cam elements actuated by the first mentioned means for causing the last mentioned means to successively feed a plurality of blanks during said thread forming relative movement of the dies, and means for adjusting the relative position of the cam elements to vary the interval of time between 85
90 the feeding of the blanks.

In witness whereof, I hereunto subscribe my name this 30th day of April, A. D., 1925.

HAROLD Langley BLOOD.
